UNITED STATES PATENT OFFICE.

ALBERT H. DREDGE, OF DETROIT, MICHIGAN, ASSIGNOR OF ONE-HALF TO
JOHN C. GOODRICH, OF SAME PLACE.

HAME-TUG.

SPECIFICATION forming part of Letters Patent No. 451,891, dated May 5, 1891.

Application filed January 26, 1891. Serial No. 379,189. (No model.)

To all whom it may concern:

Be it known that I, ALBERT H. DREDGE, a citizen of Canada, residing in Detroit, in the county of Wayne and State of Michigan, have 5 invented a new and useful Improvement in Hame-Tugs, of which the following is a specification.

This invention relates to hame-tugs, and has for its object the production of a hame-tug in which the parts are so constructed and arranged that it may be produced in a commercial form adapted to be used with any ornamental style of buckles or boxes that may be adapted to the remainder of the harness 15 with which the tug is used. To accomplish this result it is necessary that the hame-tug proper should, in the first instance, be prepared detached from the box and the buckle and arranged to be used interchangeably with 20 any style of box or buckle, and at the same time it is desirable that the box and buckle when selected may be attached readily and securely, the hame-tug attached to the hame, and the parts all secured together substantially and 25 strongly, and that this be done in an easy and practical way. I secure these results by the use of the structure described hereinafter and shown in the drawings.

Figure 1 shows the several parts of my 30 hame-tug separated from one another, and Fig. 2 shows them aggregated in the hame-tug.

The leather part of the hame-tug, which is made in the ordinary way, is represented at 35 A. It is made of two strips of leather stitched together at their edges and forming a sheath into which the long shank B of the draft-eye C slips. Through the end of the shank B is a hole D, that registers with the hole E through 40 the leather part of the hame-tug. A short flap of leather G, generally made of ornamental leather, as patent leather or embossed or stitched leather, is sewed to the outside of the sheath part A and forms a covering for a 45 portion of the piece F. The piece F is riveted to one of the two pieces forming the leather part of the hame-tug A, the rivet coming at about the point shown by dotted lines g, and one head of the rivet being concealed 50 between the parts A a and the other part being concealed between the parts A G.

The end f of the part F extends along the outside of the hame-tug, and a hole through it registers with the hole E. The end e of the piece F is formed with a mortise or opening to receive a tenon d on the end of the short shank of the draft-eye C. 55

The rear end of the piece G is cut to a width to fit snugly into the inside of the loop or box H, that forms the loop to receive the end of 60 the tug forward of the buckle I.

The buckle I is fastened into a short piece of leather turned around its hinge-rod and stitched together at the sides, forming between the sides of the leather and the stitching 65 being a sheath that slips over the end f of the piece F. A hole i registers with the hole in the end f.

The piece F, as above stated, is fixed to the leather part A, and over the end f are slipped the loop H and the buckle part I, while the draft-eye C is placed in position with the end B between A a and the end d between A G, the tenon d coming within the mortise e. A rivet J is then passed through all the holes 70 E D f i and headed down, and the parts are all secured together. The use of the rivet J prevents side motion at the buckle end of the hame-tug of the shank B within the sheath, and also forms a secure fastening for draft 75 purposes, and the engagement of the tenon d and mortise e, immediately in front of the rivet k, prevents side motion of the forward end of the draft I and the consequent cutting out of the stitches which hold the parts 80 A a g together.

In preparing the article for sale as a separate article I do not rivet down the end of the rivet J, but leave the parts in a condition such that the draft-eye C may be drawn out 85 of its sheath far enough to enable the eye of the hame to be linked into the eye of the draft-eye. By leaving the rivet J without heading it down also, the user is enabled to choose any different form or shape or ornamentation of the loop H and the buckle I to 90 correspond with the ornamentation of the other parts of the harness.

I am aware that hame-tugs have been made in which draft-eyes with long shanks were 100 used; but I am not aware of any hame-tug having one long shank and one short shank

engaging with a fixed holding-iron permanently attached to the hame-tug.

I do not wish to confine myself to the especial form of connection between the short shank 5 of the draft-eye and the fixed form F, as many different forms of connection might be employed which would be equally within the spirit of my invention.

Having described my invention, what I claim 10 as novel, and desire to have secured to me by Letters Patent, is a hame-tug composed of the following elements:

A hame-tug consisting of the parts A, a, and G, the draft-eye C, having a long shank B, a

short shank terminating in a tenon, the extension F, inserted within the sheath of the short shank of the draft-eye and terminating in a mortise and having the end f projecting to the rear and provided with a hole, the removable loop H, and the buckle I, having a 20 strip of leather turned around it and formed into a sheath to cover the rearward extension f of the part F, all arranged and combined as described.

ALBERT H. DREDGE.

In presence of—

JOHN C. GOODRICH,
EFFIE I. CROFT.
